TYPEWRITING MACHINE

William F. Helmond, West Hartford, Conn., assignor to Underwood Elliott Fisher Company, New York, N. Y., a corporation of Delaware

Application June 29, 1939, Serial No. 281,837

14 Claims.

(CL. 197—186)

This invention relates to typewriters or the like and more particularly to frame and mask structures therefor.

It is a common practice in typewriters and adding machines or the like to mount printing instrumentalities and other mechanisms upon a sturdy main frame and to dress the exposed mechanisms or unfinished surfaces thereof by ornamental covers. In most cases it is very difficult to fasten these ornamental covers to the machine proper without leaving the fastening devices exposed and consequently reducing the attractiveness and salability of the machine. In some cases the entire main frame and also the carriage has been covered by component mask-structures. Such mask structures are usually united along their joints by exposed, unsightly fastening devices.

It is an object of the invention to provide means whereby covers may be accurately registered or located upon adjoining frame or mask walls and rigidly interlocked therewith.

It is another object of the invention to eliminate exposed or apparent devices for fastening masking-covers upon the machine.

Still another object of the invention is to provide a mechanism-encasing composite mask-structure for typewriting or like machines which is cheap to manufacture, structurally strong when assembled, and pleasing in appearance.

Another object of the invention is to provide a jointed mask-structure that is conveniently and rapidly assembled upon the machine or disassembled therefrom.

A further object is to provide a mask-assembly which evidences no devices by which the component mask-parts are held together and attached to the machine.

A further object of the invention is the division of a mask into simple component mask-sections that are adapted to be joined into an extremely rigid, well-fitted, sound-proof assembly.

Another object of the invention is the provision of a unitary displaceable cover for the ribbon-spools and the type-basket.

A still further object of the invention is the provision of a common base-frame whereto the main frame as well as the component mask-parts are fastened.

The main frame of the machine is covered by a multiple-piece mask that includes two opposite side-walls having inwardly extending shoulders rising upwardly and rearwardly from the keyboard to shroud opposite front-portions of the main frame and mechanisms supported by it.

A unitary displaceable cover for both the ribbon-spools and the type-basket spans the space between the said shoulders, and a cowl or cover in back of and below the carriage covers the rear of the machine. The main frame bearing the

operating parts of the machine is seated upon a base having the form of a strong, open mask-frame and the component mask-sections are also fastened to said base and rise upwardly therefrom to cover the main frame. The several mask-parts are rigidly joined together above the base by concealed means. Some of the mask-parts are preferably joined by meshing cleats or flanges which render the composite mask-structure extremely rigid, and the joints of the composite mask simulate ornamental design lines. The carriage is masked along its sides and the rear region by a multiple-piece mask, the several pieces of which are interlocked along their joints in such manner as to substantially reduce their significance as such.

Any of the aforesaid mask-sections can be quickly removed from the machine to make repairs and adjustments at certain points of the machine without greatly disturbing the positions of the other mask-sections of the machine.

In the accompanying drawings:

Figure 1 is a perspective view of a typewriter incorporating the novel composite mask.

Figure 2 is an enlarged perspective view of a catch device that is adapted to resiliently hold a displaceable mask-section in normal, closed position.

Figure 3 is a perspective view showing the separable mask-sections of the composite mask separated from each other, and the base-frame which forms part of the means by which the composite mask is attached to the main frame.

Figure 4 is an internal perspective view of a concealed hinge-joint of a cover.

Figure 5 is a plan view of the open base-frame wherupon the main frame and the composite mask is secured.

Figure 6 is an internal perspective view showing united several of the composite mask-sections which constitute the front portion of the mask.

Figure 7 is a perspective view of the assembled typewriter including the composite mask, some of the parts of the keyboard having been left off and the unitary displaceable cover, provided to gain access to the ribbon spools and the types, having been displaced.

Figure 8 is a transverse cross-section along the dotted line 8 of Figure 5 showing a side wall of the base frame and showing a portion of one of the main frame walls and a portion of one of the masking side walls.

Figure 9 is a skeletonized perspective view showing the main mechanism-supporting frame seated upon the base frame.

Figure 10 is a rear perspective view of the assembled carriage equipped with interlocking shrouding sections.

Figure 11 illustrates a device for clamping one mask portion upon another.

Figure 12 is a sectional view along the lines 12-12 of Figure 3 showing a rear-cover and a side-wall drawn into meshed interlock by a spring-finger.

Referring now more particularly to the drawings, the typewriting instrumentalities may include an array of type-bars 10 pivotally mounted upon a segment 11 (see Figure 7) and selectively operable through actuating trains, not shown, by type keys 12 mounted upon the front-ends of key-levers 13. The front-ends of the type-bars 10 are nested in a curved type-rest 15. The typing instrumentalities 10, 12, 13 and other mechanisms including the rest 15 are supported upon an unfinished main frame seen in Figure 9 to consist of opposite side walls 14 and a number of connecting transverse bars, one of which may constitute a supporting bar 16 for the carriage-guiding rails 17 and another of which may constitute a slotted bar 18 upon which type-bar actuating parts are pivoted.

A carriage 19 seen in Figures 1, 7 and 10, is slidably mounted upon the rails 17 for movement in letter-feed and return directions and supports a platen-roll 20 against which the types 21 will strike when the type-keys 12 are operated. Type impressions may be effected by means of a transfer ribbon 23 that is threaded through openings 22 in a centrally disposed ribbon-vibrator 24 (see Figure 7) and wound upon spaced spools 25 that are supported by horizontal brackets 26 extending inwardly from the side-walls 14 of the main frame. The main frame 14, 16, 18 supports virtually all moving parts of the typewriter including also the vibrator 24.

In power operated machines, a motor 28 and a transmission housing 29 may be located below the carriage and attached to the rear-end portion of the main frame 14, 16 and 18, see Figure 9. Such motor-drive may include a belt-drive 30 to continuously rotate a power roll 31 that is operative to drive the type-bars 10 in a manner not shown, under control of the type-keys 12.

The side-walls 14 of the main frame consist preferably of punched sheet-metal plates having perforations 32 at various suitable locations so that access can be gained through the plates for making adjustments to various mechanisms such as, for example, the case-shifting mechanism, not shown.

The main frame 14, 16, 18 is seated, as seen in Figure 9, in a shallow, protecting and reinforcing base-frame 34 which is preferably a low-four-walled, rectangular, open casting or molding having two lugs 35 extending inwardly from the bottom of each of its side-walls 36. Each side-wall 14 of the main frame is provided with two threaded bosses 37, one at the front and another at the rear, which match the lugs 35 of the base-frame. Screws 38 passing upwardly through perforations in the base-lugs 35 and extending into said threaded bosses 37 secure the main frame removably to the base. As seen in Figure 9, the base-frame 34 surrounds, conceals, protects and reinforces the bottom of the main frame. Each base side-wall 36 is thickened along its full length at the bottom to form a reinforcing ridge 43 which is hollowed out underneath to form an elongate, rectangular socket-hole 39 wherein a resilient bar-shaped foot 40, preferably of rubber, is seated. The feet 40 are removably anchored to the sockets 39 by screws 41 which

are countersunk in the feet 40. A uniformly cross-sectioned bar 45 extends along the front of the keyboard and is bent rearwardly at each side to flank the opposite base side-walls 36, whereto it is fixed by concealed screws 46 passing from within through the side-walls 36 of the base. See Figures 5 and 9. The portions of the bar 45 flanking the sides 36 of the base constitute convenient finger-holds for lifting and carrying the machine. The machine may also be carried by the transverse forward bar-portion 48. The bar 45 protects the frail keyboard mechanism, and although of relatively small cross section is strong and virtually unbreakable if formed of a suitable material that can withstand shocks. Preferably the bar is die-cast of a light alloy such as a magnesium or aluminum alloy. It may, if desired, be bent from steel-tubing or formed of a non-brittle or reinforced plastic. The bar 45 is slightly flattened where it is attached to the side-walls 36 of the base and ledges 50 extending outwardly from the base overlie the bar.

The base-frame 34 not only surrounds and protects the main frame at the bottom portion thereof as hereinbefore stated but also forms the base of an assembled ornamental mask, generally designated by the numeral 51. The exterior of the base has an ornamental finish. The assembled mechanism-encasing ornamental mask 51 includes two separate opposite side-walls 52 and 53 rising upwardly from the side-walls 36 of the base 34. Each of the masking walls 52, 53 has an integral, inwardly extending, broad shoulder 54 rising upwardly from the keyboard and sweeping in a curve rearwardly toward the platen 20 slightly above the elevation of the ribbon-spools 25. The side-walls 52 and 53 are of diminished height below and in back of the carriage 19 to clear the carriage trackways 17. A low front member or connecting wall 56 between the said shoulders 54 rises a short distance upward in back of the keyboard. The clearing between the said side-wall shoulders 54, immediately above the connecting wall 56 (see Figure 7) is preferably at least coextensive with the space occupied by the array of type-bars 10 nested in the type-bar rest 15, so that the types are accessible through the clearing for cleaning. At the top, in front of the platen, the shoulders 54 have cutouts 57 to allow access to the ribbon 23 and ribbon spools 25. A unitary displaceable intermediate shrouding member or cover 59, seen in Figures 1, 3 and 7, normally fits laterally between the said side-wall shoulders 54, above the said transverse connecting wall 56 and thereby normally conceals the type-bars 10, the ribbon-spools 25 and the major part of the ribbon 23. The side-walls 52 and 53 have each underneath the carriage and in back thereof an inwardly extending stiffening shoulder or flange 60, between which there extends a rear-cover 61. The flanges 60 may extend forward of the carriage trackways 17 to form inwardly offset side-wall portions 62 adjacent to the ribbon-spools 25.

Novel devices are provided for quickly and conveniently assembling and fastening the composite mask portions 52, 53, 56, 59 and 61 together upon the machine. These devices are, according to the preferred form of the invention shown, not visible from the exterior of the machine. The individual mask portions 52, 53, 56, 59 and 61 constituting the composite mask 51 are of such form or shape as to be conveniently and economically manufactured; and when assembled

have, due to the total absence of exposed fastening devices, the appearance of a unitary mask. The joining lines of the several mask-pieces seemingly represent mere lines of the general ornamental design. The low transverse front-wall 56, as seen in Figures 1, 3, 6 and 7, has at each end at least two rearwardly extending protuberances 64 registering with holes or perforations 65 provided in flanges 66 extending laterally toward each other from the shoulders 54 of the side-walls 52 and 53. A latch lever 68 is pivoted on the inner side of each end of the front wall 56 upon a stud or pin 72. Each lever includes an arm 69 which cooperates with the adjacent flange 66 to normally clamp or hold the front-wall 56 to the adjacent flange 66 in registered position, and a lever-arm 70, constituting a handle by which the lever 68 can be manipulated. The flanges 66 are slightly offset rearwardly of the shoulders 54 so that the front side of the cover 56 and the front side of the shoulders 54 are substantially flush. The clamp arms 69 are cam-shaped to easily glide on to the flanges 66 when they are rotated from ineffective position to effective position, which positions are respectively illustrated in dotted and full lines in Figure 6. Each lever 68 is held against rotation by a strong, broad-faced spring-washer 71 underlying each lever 68 upon its pivot-pin 72. The flanges 66 constitute firm seats for the front-wall 56 so that the front-wall 56 and side-walls 52 will be clamped together to a firm structure. The protuberances 64 are preferably in the form of pins riveted to the front-wall 56 and these pins including the pins 72 are flush with the front-face of the wall 56 and therefore externally invisible. The wall 56 has several vertical slots 74 to accommodate key-levers extending rearward from the keys 16 that are associated with the tabulating mechanism of the machine. The wall 56 has at the top a rearwardly-turned flange 81 rendering it strong and rigid.

The transverse rear cover or shrouding member 61 is seen in Figure 3 to have a straight vertical wall 73 merging into a forwardly extending portion consisting of a raised cowling 75 extending underneath the carriage and dropping downwardly at each end to be substantially continuous with the side-wall flanges or shoulders 60. The cover 61 shrouds mainly the electric motor 28 and the transmission housing 29 seen in Figure 9. A lateral slit 77 seen along the rear edge of the cowling 75 provides an escape for the heat generated by the motor 28.

Efficient means are provided whereby also the transverse rear-cover 61 is accurately registered relative to the opposite side-walls 52 and 53. More specifically, each lateral end of the cover 61 has an integral cleat or ridge 78 which fits a groove formation or cleat 79 provided on the adjacent side-wall flange 60. See Figures 3 and 12. The associated cleats 78, 79 at each end of the cover or wall 61 constitute intermeshing tongue-and-groove joints between the side-walls 52 and 53 and the cover 61 along each cover-end, whereby they are accurately registered and rigidly interlocked. The side-walls 52, 53 and the rear-cover 61 of the mask are stiffened by inwardly extending bottom flanges 83 and 84 respectively (see Figures 1, 3 and 8), which are widened at several points and provided with threaded holes 85 that overlie corresponding vertical perforations 86 in lugs 87 extending inwardly from the walls of the base-frame 36. Screws 88 passing upwardly through the base-perfora-

tions 86 extend into the threaded holes 85 to fasten the side-walls 52 and 53 and the rear-cover 61, in intermeshed registration upon the base. The holes 86 in the base are countersunk and slightly oversized, as seen in Figure 8, to allow for manufacturing differences in the mask-parts 52, 53, 56 and 61. In assembling the mask upon the machine, the side-walls 52, 53 and the rear-cover 61 are clamped to the base by means of said screws 88 in exactly relatively registered positions. Said oversized holes 86 give sufficient freedom to effect this, irrespective of the manufacturing differences. The side-walls 52, 53 and the rear-cover 61, when anchored by the screws 88 to the base, form a firm, interlocked, self-sustaining mask-structure, rising upwardly from the base 36 out of contact with the framework, and no means are visible or apparent whereby the composite mask is supported on the main frame 14, 16, 18. The side-walls 52 and 53, although only fastened to the main frame at the bottom, through the medium of the base 36, are extremely well braced in their upright positions by the rear-cover 61 through the invisible interlocking tongues and grooves 78 and 79 and also through the registering devices 64, 65 of the front-wall 56. The tongues and grooves are so arranged upon the side walls 52 and the rear shrouding member that the latter is readily removable from the side walls. In the form of the invention shown, the screws 88 fastening the rear-cover 61 to the base 36 are supplemented in the function of holding the side-walls 52, 53 and rear-cover 61 together through concealed devices seen in Figures 3 and 12, which resiliently draw the rear-cover rightly registered upon the side-wall cleats 78. These devices comprise spring-fingers 90 riveted to opposite interior upper end-positions of the cover 61 that normally extend at their free ends under lugs or pins 91 on the side-wall flanges 60. The rear-cover 61 is quickly assembled upon the side-walls 52 and 53 by sliding the cover along the side-wall cleats 78 so that the resilient fingers 90 will slide under the pins 91 and thereby will draw the cover-cleats 78 into full mesh with the opposite side-wall cleats 79. The spring fingers 90 together with the screws 88 keep the side walls 52, 53 and the rear-cover 61 tightly interlocked upon the base and the creation of vibratory noises in the cleat-joints is avoided. It should be understood that it may suffice to hold the rear-cover interlocked directly with the side-walls without fastening it to the base. Any of the individual mask-portions 52, 53, 56 and 61 can be temporarily removed to expose certain mechanisms, such as for example the case-shift adjusting mechanism, without removing any other mask-portion or portions from the machine.

The unitary cover 59 has a forward type shrouding portion 89 that is substantially equal in width with the nest of types 21 and blends into a rearwardly disposed, horizontal top-portion 94 (see Figure 1), that spreads outwardly over the ribbon-spools 25 seen in Figure 7. The ribbon-spools 25 and the types 10 are therefore normally fully covered and the cover 59, being in interfitting engagement between the side wall shoulders 54, forms therewith a substantially continuous front and top face. The entire cover 59 pivots along an axis parallelly adjacent to the platen carriage. More specifically as seen in Figure 4, two opposite rectangularly bent brackets 92, secured by rivets 95 to the underside 75 of the cover 59, near opposite ends thereof, have

each a downwardly pending branch 99 provided with an L-shaped slot-opening 96, whereby the opposite ends of the cover 59 are pivotally seated upon two opposite pivot posts 93 projecting inwardly from the side-walls 52 and 53 of the mask. A spring 97 connected to a bracket-ear 98 draws the brackets 92 and therefore the cover 59 resiliently downward about the pivot-posts 93. The springs 97 are preferably anchored to pins 98 on opposite side-walls 14 of the main frame. When the cover is displaced upwardly and rearwardly to the position shown in Figure 7, the springs 97 cross the center of the pivot-axis and thereby will act to hold the cover 59 in open position, whereat it may lean against the platen 20. In this position the type-bars are accessible for cleaning and also the ribbon may be changed. The slots 96 are L-shaped and open toward the rear as seen in Figure 4 in order to allow the removal of the cover 59 in its open position from the pivot-pins 93. The springs 97 are, however, preparatory to the removal of the cover, unhooked at either of their ends. It should be noted that the tendency of the cover-brackets 92 to unseat from the pivot-pins 93 is normally resisted by the action of the springs 97. The cover 59 is normally in interfitting position between the mask shoulders and has integral cleats 103 along its side edges, which cleats normally mesh with groove-cleats 104 integral with the opposite inner edges of the mask-shoulders 54. The grooves 105 of the cleats 103 face forwardly and the associated cleats 104 on the cover face toward the rear. Thus the cleats 103 and 104 are capable of separation when the cover is swung open. Aside from having the function of accurately registering the cover upon the side-wall shoulders 54, the cleats 103 and 104 reinforce and support the cover in closed position and also brace the front-portion of the assembled mask, particularly the upper front portions of the side walls 52. The cover 59 has a central cut-out 107 adjacent to the printing point directly in front of the platen 20 to provide a clearance for the types 21 to move against the platen. Similarly, the top-portion 94 of the cover has a slight raise intermediate the ribbon-spools 25 to provide on the underside of the cover a passage 108, see Figure 7. The cover spreading over the ribbon-spools 25 is low enough to leave the full typing line 106 exposed, see Figure 1. The cover 59 has at the front a finger-hold in the form of an attached button 109. Clips or detents 111 (see Figures 2 and 6) attached along the back-side of the cover at the bottom, in conjunction with pins 112 projecting upwardly from the flange 81 on the transverse wall 68, resiliently hold the cover 59 in closed position. The clips 111 are arranged in integral pairs riveted to the back-side of the cover of which each pair engages the opposite sides of one of the pins 112. The clips of each pair are flared outwardly from each other to form tapered pin-receiving throats 113 and have also detenting seats 114, see Figure 2.

Describing now the typewriter carriage 18, illustrated best in Figures 7 and 10, the platen 20 is revolvably secured upon opposite carriage end-plates 115. The end-plates 115 are mounted on opposite ends of a bar 116 that is guided for letter-feeding and carriage-return movements upon the stationary trackways 11. The carriage also includes a rack 117 which carries a set of tabulator-stops 118. These tabulator stops are individually settable from a key 16 in the keyboard through a stop-setting member 119 ex-

tending upwardly from a stationary column 120 protruding upward through a cut-out 121 in the rear cover 61, seen in Figure 3. A paper-table 123, substantially coextensive with the platen 20, pivots on an axis 125 directly in back of the platen and extends normally upwardly and rearwardly thereof to overlie a rack 126 having margin-stops 127 adjustable thereon. The table 123 rests normally against a stationary part on the carriage, not shown, but can be swung forward about the axis 125 to gain access to the stops 127 for adjusting them. The tabulator rack 117 is situated in back of the margin-stop rack 126 and is with other mechanisms including parts 111, 119, concealed by a hood or shroud 129, extending from end to end of the carriage and having a horizontal top-shelf 130 and a downwardly pending rear-wall 131. The shroud, hood or cover 129 is flanked by opposite side-covers 133 and 134, covering the end-plates 115 of the carriage. The side-covers 133 and 134 may be attached to the carriage-ends 115 by any suitable means. These means may or may not be concealed. In the form of the invention illustrated in the drawings, the side-covers 133, 134 are fastened to the end-plates 115 of the carriage by means of screws 136. The side-covers are preferably spaced from the end-plates 115 by sound insulating spacers, such as bushings 137 of fairly hard rubber. The side-walls have wide flanges 138 extending toward each other and covering the end-plates 115 at the front, top and back. The shelf 130 and the rear-wall 131 of the hood 129 are substantially flush with the side-wall flanges 138 at the top and rear. In order to fasten the hood 129 in correct position relative to the side-covers 133 and 134 to thereby provide a well-jointed, rigid mask-assembly, it is conceived to provide means to register and lock the side covers 133, 134 and the hood 129 upon each other. The side-wall flanges 138 for this purpose have along the inner edges where they join the hood 129, tongues or cleats 141 whereupon the hood is accurately seated or registered by U-shaped ears 142 provided along both ends of the hood 129. In the drawings, three such ears 142 are shown to hook over the rim 141 of each side cover, one on top and two at the back. Continuous grooved cleats may be provided instead of the several ears 142. The ears 142 in effect form sockets 143 into which the tongues 141 of the adjacent side-covers 133, 134 extend. The hood 129 is removably held in meshed interlock at each end upon the sockets 143 by easily accessible means that are concealed within the assembled carriage-mask. According to the embodiment of the invention shown, a clamp arm 144 at each carriage end is secured by a screw 150 to a laterally-turned ear 145 of a rearwardly extending bracket-arm 146 fastened to one of the carriage-end plates 115. The clamp-arms 144 have cam-edges 147 to engage the underside of forward projections 153 on the hood ends. In order to position the hood 129 in registered position upon the side-walls, the clamp screws 150 are loosened and the clamp-arms 144 are turned outwardly, clear of the projections 153. After the hood is properly seated in respect to the side-walls, the clamp arms 144 are swung toward each other to wedge the hood 129 tightly upward. The top ends of the clamp-arms 144 lie in front of forwardly projecting abutments 154 on the hood-ends and will press the hood rearwardly when the clamp screws 150 are being tightened. The clamp arms 144 may be slightly resilient and

the bracket-ears 148 so located relative to the abutments that the arms 144 will bend as seen in Figure 11 when drawn tightly against the bracket-ears 148 by the screws 156.

A convenient procedure to assemble the carriage mask consists of first loosely screwing the side-covers 133, 134 to the carriage end-plates 115, to secondly introduce the hood 129 intermediate the side covers, to thereafter tighten the clamps 144 and last to tighten the screws 136. This procedure, however, need not be followed. Either end-cover 133 or 134 may be removed without removing the other. If it is desired to remove the hood 129, either one or both of the end-covers 133, 134 may be loosened by the screws 136 to enable the withdrawal of the hood. The hood 129 has a downwardly-turned lip 151 at the front that extends a short distance underneath the paper apron 123. The several mask-portions 133, 134, 129 of the carriage are preferably struck up from thin aluminum sheeting and the above-described novel interlocking joints render the composite structure thereof extremely rigid and well-connected, notwithstanding the relative frailness of the independent pieces.

The several mask-sections covering the stationary part of the machine rise upwardly from the base 34 free of the main framework 14, 16 and 18 and the several mask sections are fastened together independent of the mechanism-supporting frame and are therefore self-sustaining. The mask, as seen in Figure 8, is sound insulated from the main frame by rubber washers 155 introduced between the bosses 37 and the base lugs 35. The individual mask parts may be molded of a plastic material, die cast, or pressed up from sheet-metal, such as preferably of a magnesium alloy or aluminum alloy.

It is to be understood that the various means shown for registering and fastening certain mask-parts together may also be used to advantage to fasten certain other machine covering parts together. The base frame 34 although used to great advantage is not to be considered an essential part of the invention. Certain mask parts may be used without using others. The side-frame pieces 14 may constitute themselves finished side-walls to which masking-walls or covers are removably or displaceably joined in accordance with this disclosure.

What is claimed is:

1. In a typewriter, a mechanism-encasing composite mask comprising oppositely disposed spaced side walls provided with rear and top shoulders, a rear intermediate shrouding member defining a rear wall and a forwardly extending portion, and tongue and groove formations on said rear intermediate member and at least one of said shoulders on each side wall, fitting each other in a manner to interlock rigidly said side walls with the intermediate member laterally and to render said intermediate member removable from said side walls, said rear intermediate member fitting the shoulders of the opposite side walls in a manner to provide a rear wall and forwardly extending portion which is substantially continuous with the shoulders of the side walls at both top and back of the mask.

2. In a typewriter, a mechanism-encasing composite mask comprising a base member, oppositely disposed spaced side walls anchored to said base member and provided with rear and top shoulders, a rear intermediate shrouding member defining a rear wall and a forwardly extending portion, and tongue and groove formations on said rear

intermediate member and at least one of said shoulders on each side wall, fitting each other in a manner to interlock rigidly said side walls with the intermediate member laterally and to render said intermediate member removable from said side walls, said rear intermediate member fitting the shoulders of the opposite side walls in a manner to provide a rear wall and forwardly extending portion which is substantially continuous with the shoulders of the side walls at both top and back of the mask.

3. In a typewriter, a mechanism-encasing self-sustaining composite mask comprising two oppositely disposed side walls each having a front shoulder extending toward the other, an intermediate rear shrouding member firmly connecting said side walls at the rear, and an intermediate front and top shrouding member comprising ribbon spool covers and a type shroud section, said shoulders and said front intermediate member having tongue and groove formations fitting each other in a manner to interlock rigidly said side walls at the front laterally with said front intermediate member and to render said intermediate member displaceable, said shoulders being formed and said front intermediate member fitting the said shouldered side walls in a manner to present therewith a substantially continuous front and top mask face.

4. In a typewriter, a mechanism-encasing self-sustaining composite mask comprising two oppositely disposed spaced side walls each having a front shoulder extending toward the other, and a hingedly mounted intermediate shrouding member comprising ribbon spool covers and a type shroud portion, said shoulders and said intermediate member having tongue and groove formations fitting each other in a manner to interlock rigidly said side walls laterally with said intermediate member and so that said intermediate member is associateable with the side walls for hinged movement to and from shrouding position, said shoulders being formed and said intermediate member fitting the said shouldered side walls in a manner to present therewith a substantially continuous front and top mask face.

5. In a typewriter, a mechanism-encasing self-sustaining composite mask comprising two oppositely disposed spaced side walls each having a front shoulder extending toward the other, and a hingedly mounted intermediate shrouding member comprising ribbon spool covers and a type shroud portion, said shoulders and said intermediate member having tongue and groove formations fitting each other in a manner to interlock rigidly said side walls laterally with said intermediate member so that said intermediate member is associateable with the side walls for hinged movement to and from shrouding position, and detent means adapted to releasably hold the intermediate member in shrouding position with the tongue and groove formations in interlocked engagement.

6. In a typewriter, a mechanism-encasing mask comprising two oppositely disposed side walls each having a front shoulder extending toward the other, a low front member connecting said side walls at the lower regions of said shoulders, a displaceable intermediate front and top shrouding member comprising ribbon spool covers and a type shroud section, said shoulders and said intermediate member having tongue and groove formations fitting each other in a manner to interlock rigidly said side walls at their upper regions laterally with said intermediate member

and to render said intermediate member displaceable, and cooperative means on both said members for releasably detenting said shrouding member in interlocked relation with the said side walls.

7. In a typewriter, a mechanism-encasing mask comprising two oppositely disposed side walls each having a front shoulder extending toward the other, a low front member connecting said side walls at the lower regions of said shoulders, a displaceable intermediate front and top shrouding member comprising ribbon spool covers and a type shroud section, said shoulders and said intermediate member having tongue and groove formations fitting each other in a manner to interlock rigidly said side walls at their upper regions laterally with said intermediate member and to render said intermediate member displaceable, said shoulders being formed and said intermediate member being adapted to fit the said shouldered side walls in a manner to present therewith a substantially continuous front and top mask face, and cooperative means on both said members for releasably detenting said shrouding member in interlocked relation with the said side walls.

8. In a typewriter, a mechanism-encasing composite mask comprising a base frame having side and rear masking walls, separate oppositely disposed side walls anchored to the said base frame and provided with rear and top shoulders, a rear intermediate shrouding member defining a rear wall and a forwardly extending portion, and tongue and groove formations on said rear intermediate member and said shoulders fitting each other in a manner to interlock rigidly said side walls and intermediate member laterally and to render said intermediate member removable from said side walls, said rear intermediate member fitting the shoulders of the opposite side walls in a manner to provide a rear wall and forwardly extending portion which is substantially continuous with the shoulders of the side walls at both top and back of the mask.

9. In a typewriter, a mechanism-encasing self-sustaining composite mask comprising an open base frame having side and rear masking walls and machine-supporting means within said walls, oppositely disposed side walls anchored to the said base frame and provided with rear and top shoulders, a rear intermediate shrouding member defining a rear wall and a forwardly extending portion, and tongue and groove formations on said rear intermediate member and at least one of said shoulders on each side wall, fitting each other in a manner to interlock rigidly said side walls and intermediate member laterally and to render said intermediate member removable from said side walls, said rear intermediate member fitting the shoulders of the opposite side walls in a manner to provide a rear wall and forwardly extending portion which is substantially continuous with the shoulders of the side walls at both top and back of the mask.

10. In a typewriter, a mechanism-encasing self-sustaining composite mask comprising oppositely disposed spaced side walls provided with front shoulders and rear shoulders, a hingedly mounted intermediate front shrouding member, comprising ribbon spool covers and a type shroud portion, said shrouding member being normally positioned to present with said shouldered side walls a substantially continuous front and top

face at the front of the machine, a rear intermediate shrouding member defining a rear wall and a forwardly extending portion, and tongue and groove formations on said rear intermediate member and said rear shoulders, fitting each other in a manner to interlock rigidly said side walls and rear intermediate member laterally and to render said rear intermediate member removable from said side walls.

10 11. In a typewriter, a mechanism-encasing self-sustaining composite mask comprising oppositely disposed spaced side walls provided with front shoulders and rear shoulders merging into top shoulders, a hingedly mounted intermediate front shrouding member, comprising ribbon spool covers and a type shroud portion, said front shrouding member being normally positioned to present with said shouldered side walls, a substantially continuous front and top face at the front of the machine, a rear intermediate shrouding member defining a rear wall and a forwardly extending portion, and tongue and groove formations on said rear intermediate member and said rear shoulders, fitting each other in a manner to interlock rigidly said side walls and rear intermediate member laterally and to render said rear intermediate member removable from said side walls, said rear and top shoulders being formed and said rear intermediate member fitting the rear and top shoulders of the opposite side walls in a manner to provide a rear wall and forwardly extending portion which is substantially continuous with the rear and top shoulders of the side walls at both top and back of the mask.

12. In a typewriter, a mechanism-encasing composite mask comprising, oppositely disposed spaced walls provided with shoulders extending toward each other, an intermediate shrouding member, and tongue and groove formations on said intermediate member and said shoulders, fitting each other in a manner to interlock rigidly said spaced walls with the intermediate member laterally and to render said intermediate member displaceable from said spaced walls.

13. In a typewriter, a mechanism-encasing composite mask comprising, oppositely disposed spaced walls provided with shoulders extending toward each other, an intermediate shrouding member, and tongue and groove formations on said intermediate member and said shoulders, fitting each other in a manner to interlock rigidly said spaced walls with the intermediate member laterally and to render said intermediate member displaceable from said spaced walls, said shoulders being formed to accommodate said intermediate member in a manner to present therewith a substantially continuous external face.

14. In a typewriter, a mechanism-encasing composite mask comprising, oppositely disposed spaced side walls provided with rear shoulders merging into top shoulders, an intermediate shrouding member defining a rear wall and a forwardly extending portion, and tongue and groove formations on said intermediate member and said shoulders fitting each other in a manner to interlock rigidly said side walls with said intermediate member laterally and to render said intermediate member removable from said side walls.

WILLIAM F. HELMOND.
